Fig. 2

The diagram illustrates a head rail assembly. A vertical 'Head Rail' (5) is shown on the left, with a horizontal '5a' section extending from its side. A '4a' section is attached to the top of the vertical rail. A '4' section is positioned above the '4a' section. A '54' section is attached to the side of the vertical rail. A '4a' section is attached to the top of the '54' section. A '4' section is positioned above the '4a' section. A '12' section is attached to the side of the vertical rail. A '4' section is positioned above the '12' section. A '4' section is positioned above the '4' section. A '4' section is positioned above the '4' section.

APPARATUS FOR ASSEMBLING VENETIAN BLINDS

Harry S. Rosenbaum, Baltimore, Md.

Application April 3, 1952, Serial No. 280,210

31 Claims. (Cl. 29—24.5)

This application relates to apparatus for assembling Venetian blinds, particularly Venetian blinds having metal slats. It is a continuation-in-part of my copending application Serial No. 238,528 filed July 25, 1951, now abandoned.

Venetian blinds are a well-known article of commerce and require no description. The apparatus which I have invented cuts slats for Venetian blinds to the proper length, punches holes at the proper places in the slats for the lift cords, feeds the slats so cut and punched between the side and cross tapes of conventional Venetian blind ladder tapes and, at the same time, threads blind lift cords through the holes which have been cut in the slats for these cords. Finally, my apparatus carries away the blind after it has been assembled to a position where it can be finished by operators who tie on the bottom rail, draw up the blind, and otherwise prepare the blind for shipping.

Heretofore the assembly of Venetian blinds has been a significant part of the cost of manufacturing the blinds because a large amount of manual labor has been required in this operation. Thus it has been the practice to assemble a head rail with a tilt bar and a cord lock therein, together with the operating cords, namely, the lifting cord and the tilting cord. The ladder tapes are fastened to the tilt bar and the entire assembly is placed on an overhead conveyor which slowly moves the assembly past a number of workers, each of which stands or sits to work at particular heights and slide the individual slats in position in the ladder tapes. After the slats have been inserted, the conveyor carries the assembly past additional workers who thread the lifting cords through the slats, fasten a bottom rail to the lower ends of the lifting cords, pull up the blind to a closed position and lift the blind from the conveyor for packing. Such an assembly line requires from 15 to 20 workers.

Because of the number of workers required in the assembly operation just described, the best operating costs now prevailing in this country for this operation are approximately \$.52 for a blind of average size, i.e., 13 square feet.

By my invention, I am able to reduce the number of workers required for assembly to such an extent that the cost for assembly of an average blind is \$.10. My invention also materially reduces the amount of floor space required for the assembly operation in the manufacture of Venetian blinds. A conventional production line, such as just described, is generally 85 to 100 feet long, whereas my machine is approximately 16 feet long.

Venetian blinds are necessarily manufactured in a number of different widths and the spacing of the ladder tapes is, of course, dependent upon the width of the blind. An important feature of my invention is that the dies for cutting and punching the slats and the apparatus for assembling the slats and tapes can be easily positioned for a large variety of blind lengths. The spacing of the dies and of the assembly machines is accomplished without calculation and without measuring simply by placing

2

a head rail on supports in the machine and bringing a movable stop up to the end of the head rail. This automatically determines the setting of the machine for cutting the slats, punching holes therein and assembling the slats in the tapes.

For use in my machine, the tapes are cut to the required length before they are fed to the machine. I have invented a novel method of preparing the tapes whereby long lengths of ladder tape are cut to form tapes a required length, but wherein, and as part of the same operation, the cut lengths are secured to each other so that the tapes, although cut, can be fed continuously to my assembly machine. During operation of the machine, the separate cut lengths can easily be separated from each other by the operators.

In the accompanying drawings, I have illustrated certain present preferred embodiments of my invention, in which—

General description

Figure 1 shows a front elevation of my entire machine. This machine handles slats which are fed to the machine

40 in long lengths from coils on a conventional rotating feed table or directly from a slat forming machine. The feed table and the forming machine are conventional and are not shown in Figure 1. The machine itself comprises a cutting and punching section, designated generally by the

45 reference letter A, an assembly section, designated generally by the reference letter B in which the slats are passed into the ladder tapes, lifting cords are threaded through lifting cord holes in the slats, and the slats are lifted out of the way for the succeeding slats. Finally,

50 there is a blind conveyor section, designated generally by the reference letter C, which removes the assembled slats and tapes away from the assembly section while they are being assembled and carries them to another position on the machine where operators can secure the bottom

55 rail to the lift cords, close up the blind and prepare it for packing. The machine is continuous in its operation, that is, at the same time a slat is being cut to length and punched in section A, another slat is being assembled with the ladder tapes and lifting cords at section B, and

60 assembled slats, tapes and cords are being carried away by section C.

Section A, which cuts the slats to length and punches holes in the slats for the lifting cords, comprises a conventional slat cutting die 1 which has two cutting edges

65 whereby one stroke cuts the rear end of one slat and the front end of the succeeding slat. The section also has a die 2 for cutting a hole in the slat for a lift cord. The dies 1 and 2 are fixed in position in this section and are spaced from each other the usual distance between

70 the end of a slat and the first tape (approximately 6 inches). The section also has another die 3 for cutting additional holes in the slats as required. This die is movable with respect to the other two dies so that slats of different lengths with properly spaced lifting cord holes can be made.

The assembly section has a threading head 4 for each ladder tape. My machine can handle any number of tapes. The machine shown in Figure 1, however, is designed for 2, 3 or 4 tapes, four tapes being the maximum now generally used.

An important feature of the threading heads is that, during assembly of the blinds, the motion of the slat moves the tape through the threading head. After a slat has been passed between the side tapes and cross tapes of a ladder tape, the threading head lifts the slat out of the path of the succeeding slat. This lifting motion pulls the tape through the threading machine. Ladder tapes for Venetian blinds are a relatively low-priced commercial product which are made in a number of grades and which, therefore, are subject to considerable variation in the spacing of the tapes, particularly the cross tapes. By having the slats move the tapes through the machine, the problem of commercial tolerances in the tapes is avoided.

The threading heads also thread lifting cords through holes therefor in the slats and between the cross tapes of the ladder tapes, which cross tapes are conventionally secured along alternate edges of the side tapes.

The threading heads can retain a considerable number of assembled slats, tapes and lifting cords in slat supports 5 carried by the threading heads 4 (see Figure 2). However, I also provide a blind conveying section C to carry off the tapes and slats after they are assembled and move them to another place where the finishing operations can be performed. Thus one blind can be assembled while the preceding blind is being finished for packing and shipment.

The blind conveying section comprises two endless chains 6 and 7, one at each end of the assembly section, which carry two cross bars 8 and 9. The cross bars in turn have brackets 10 in which a head rail can be placed. One bracket is adjustable on each cross bar so head rails of different lengths can be carried. In the drawings, the right-hand bracket (viewing Figure 1) is shown as adjustable.

The chains are guided by sprocket wheels 11 so that the brackets 10 pass through a point adjacent the slat supports 5 on the threading heads (see Figure 3). An operator places a head rail in the supports 5 (see Figure 2), secures ladder tapes to a tilt bar in the head rail and then places the head rail in the brackets 10. The operator also secures lifting cords carried by the head rail to lifting cord needles in each threading head, as will later be described. As the slats and tapes are assembled and accumulated in the supports 5, the cross bars carrying the head rails move vertically upward until all of the slats for a blind of the size being assembled have been inserted in the tapes. The bars next move generally horizontally to the rear of the machine (viewing Figure 3). At this position operators can secure a bottom rail to the tapes and to the lifting cords. The cross bars and the head rails then continue vertically downward to a position where the head rail and the entire blind can be lifted from the brackets carried by the cross bars. During this downward movement an operator can raise the slats by pulling on the lifting cord and otherwise prepare the blind for packaging.

The endless chains and the blind conveying mechanism can be driven so that the motion of the head rails is indexed with the threading heads. In other words, the conveying mechanism moves intermittently with the operation of the threading heads, the conveyor moving a short distance each time a slat is threaded into the cross tapes. The conveyor can also be moved independently of the threading heads so that a number of slats with tapes can be stacked in the slat supports 5 on the threading heads while the operators are securing the ladder tapes to the tilt bars, following which the conveyor is speeded up to carry off the slats which have accumulated. Alternatively, the conveyor can move continuously with

automatic stops at certain positions where manual operations have to be performed, such as placing head rails in the brackets and securing the ladder tapes to the tilt bar or securing the bottom rails to the blinds.

5 There are two sources of power for the entire machine. The chief source of power is housed at the right-hand end of the machine (viewing Figure 1) and includes an electric motor, gearing, clutches, etc., to drive in correct synchronism all the threading heads, the die 1 which cuts the slats to length, the die 2 which cuts some of the lifting cord holes in the slats, and the blind conveying mechanism. All of the threading heads and the two dies just mentioned are driven through a common shaft 12 which extends the entire length of the assembly section B and partially into the cutting and punching section A so as to operate dies 1 and 2. A separate motor housed in the cutting and punching section operates slat feeding rolls 13 and (when blinds having more than two tapes are being assembled) the adjustable die 3 which cuts 15 additional holes in the slats for lifting cords.

Cutting and punching section

This section of my machine is shown in Figures 5 and 6. The cutting and punching section comprises three conventional dies, a cutting die 1, which cuts the rear end of one slat and the front end of the next slat on the same stroke, and dies 2 and 3 for punching holes in the slats for lifting cords. The cut made by die 1 is shown in actual size in Figure 7 of the drawings and the hole punched by the dies 2 and 3 is shown in actual size in Figure 8. The dies 1 and 2 are fixed to a base 14 and the die 2 is spaced from the die 1 the customary distance between the end of a slat and the first lifting cord hole (approximately six inches). The die 3 is movable in 20 ways 14a forming part of the base 14 towards and away from the die 2 (see Figure 6).

U-shaped guides 15 for the slats extend between the dies. Because the position of die 3 is movable with respect to die 2, the portion of the guide 15 between the dies 20 and 3 is made in sections which telescope within each other.

A pair of conventional slat feeding rollers 13 feed slat material from a forming machine or feeding table through the dies. A motor 16 mounted in a cabinet 17 beneath the base 14 (see Figure 1) drives the upper roller of the two rollers 13 through a speed reducer 18 and a belt and pulley drive 19. In the operation of my machine, the motor 16, and therefore the upper of the rollers 13, are driven continuously. The upper roller is driven through a conventional slip clutch so that movement of the slat material through the machine can be stopped by the dies or by the threading heads 4 as will be later described. The front of the cabinet 17 carries a switch panel 17a for several toggle switches, one of which controls the supply of current to the motor 16 (see Figure 68).

As shown in Figures 9 and 10, the dies 1 and 2 are driven by the common or main shaft 12 through a crank 20, crank lever 21 and crank 22 mounted on a common 60 operating shaft 23. The die 3 is driven by the motor 16 through a belt and pulley drive 24 (see Figures 5 and 9). For purposes of clarity, only two pulleys of the drive are shown in Figure 5, a conventional dog clutch 25, shaft 26, crank 27, crank lever 28, crank 29 and operating shaft 30.

65 As will be later described, microswitches carried on the threading heads 4 control the operation of the dog clutch 25 and of a clutch (hereinafter described) connected to the shaft 12 and thereby the dies 1, 2 and 3 are operated in timed sequence. The switches and their 70 operation will be later described. However, when blinds having only two tapes and only two lifting cord holes in the slats are being assembled, the dies 1, 2 and 3 are all driven by the shaft 12. In order to drive the die 3 by the shaft 12, I provide a hand-operated lock, design-

nated generally by the reference number 31, for connecting together the operating shafts 23 and 30.

The lock 31 is shown in Figure 9 of the drawings and includes a lever 32 keyed to the shaft 30 and a second lever 33 keyed to the shaft 23. It also includes the crank 29 on the shaft 30. The lever 32 carries a pin 34 which extends parallel to the shaft 30 and which can be slid in the lever 32 so as to project out either side of the lever. The pin has a handle 34a which extends out of a slot cut in the front of the lever 32. When the shafts 23 and 30 are to be operatively connected, the pin 34 is slid into a hole 35 in the lever 33 and in line with the pin 34. When the pin 34 is in the hole 35, rotation of the shaft 23 and the lever 33 will turn the lever 32 which is keyed to the shaft 30.

When the die 3 is to be operated separately from the dies 1 and 2, the pin 34 is moved to the left (viewing Figure 9) to insert it into a hole 29a in the crank 29. When the pin 34 is in that position, the lever 32 can move only with the crank 29.

Length adjustment

Venetian blinds necessarily must be made in varying widths so as to fit a wide variety of windows and the right number of tapes must be provided in accordance with the width of the blind. Likewise, an appropriate number of holes for lifting cords must be provided in the slats. In the machine shown in this application, I can assemble blinds in widths varying from twenty-two inches, in which only two tapes and two lifting cords are used, up to one hundred and two inches, in which four tapes and four lifting cords are used. The machine could be arranged to cut and assemble blinds which are wider than ninety inches and which require an additional number of tapes and lifting cords by adding additional threading heads. However, ninety inches is the maximum width now generally manufactured and sold. In my machine, I can also cut and assemble blinds of intermediate widths in which three ladder tapes are used but in which only two lifting cords are used.

As previously stated, the dies 1 and 2 are fixed. The threading head 4, which is nearest the die 1, is also fixed in position, but the other threading heads are movable horizontally away from the fixed threading head on rails 4a (see Figures 2 and 19) so that the proper spacing can be obtained for the tapes of a blind of any given length. As noted, the die 3 is also movable to provide properly spaced lifting cord holes. I provide means whereby the position of the movable die 3 and the movable threading heads 4 can be set without calculating and thereafter measuring the correct positions of the movable die and of the movable threading heads. Each slat support 5 on the threading heads 4 carries a bracket 5a on which a head rail for the particular blind being assembled can be placed (see Figures 2 and 19). I also provide a movable bracket 36 (see Figures 12, 13 and 14) which can be detachably secured to any one of the movable threading heads. The threading head to which the bracket is secured is determined by the number of tapes required for a particular blind being assembled. Thus, if a two tape blind is being assembled, the first movable threading head away from the fixed threading head carries the bracket 36. If a three tape blind is being assembled, the second movable threading head carries the bracket and, finally, if a four tape blind is being assembled, the threading head on the right-hand end of my machine (viewing Figure 1) carries the bracket. The bracket 36 carries a stop 36a which may be brought up against one end of the head rail resting in the brackets 5a. By mechanism to be described, the threading head carrying the bracket 36 is then moved to the left (viewing Figure 1) until the left-hand end of the head rail abuts the side of the die 1. This movement of the threading head carrying the bracket 36 and stop 36a determines

the position of the other threading heads and of the movable punch die 3.

The bracket 36 may be detachably secured to the right hand (viewing Figure 1) of the two slat supports 5 carried by each of the movable threading heads. As shown in Figures 12, 13 and 14, the bracket has a base 36b in the form of a plate which slides into gibs 36c on the slat support. The bracket has a plate which extends toward the front of the machine into the path of travel of the slats and which forms the stop 36a.

Figures 15, 16, 17 and 18 show the mechanism for adjusting the movable threading heads and punching die to the correct position in accordance with the length of the head rail for the blind being assembled. The mechanism includes rack bars 37, 38 and 39, each of which is secured at one end to one of the movable threading heads 4 (see Figure 19). The lower edges of the bars have rack teeth which mesh with pinions 40, 41 and 42, all of which are mounted on a common shaft 43. The shaft 43 carries another pinion 44, which meshes with a pinion 45 carried on a shaft 46. The shaft 46 carries a handwheel 47 by means of which the shaft 43 can be turned. The pinions 40, 41 and 42 are all of different diameters so that rotation of the common shaft 43 (and thereby each of the pinions 40, 41 and 42) will move the rack bars 37, 38 and 39 different distances proportional to the difference in the diameters of the pinions 40, 41 and 42.

A series of flanged wheels 48 all turning on a shaft 49 ride on top of the rack bars 37, 38 and 39 in order to hold the bars down into engagement with the pinions 40, 41 and 42.

As appears in Figures 5, 6, 15, 16 and 17, the rack bar 39 extends beyond the pinion 42 and beneath the base 14 of the cutting and punching section A. The end of the rack bar which extends into the cutting and punching section has rack teeth on its upper edge. These teeth mesh with a pinion 50 secured to a shaft 51 rotatably supported from the base 14. The shaft 51 also has a pinion 52 which meshes with a second rack bar 53, the left-hand end of which (viewing Figures 5 and 16) is secured to the movable die 3.

To set the position of the movable die 3 and the movable threading heads 4, the operator turns the handwheel 47 until the stop 36a on the bracket 36 (previously mounted on the outermost head rail being used) has moved a head rail on the brackets 5a up against the side of the cutting die 1. When the ends of the head rail lightly engage both the side of the die 1 and the stop 36a, the die 3 and the movable heads 4 are all in correct position to cut and punch slats of the right length for the head rail and to assemble the tapes in their proper spaced position along the slats.

Threading heads

As heretofore stated, the slat assembly section has a plurality of threading heads 4, one head being provided for each ladder tape. The several threading heads are all identical in construction and operation, except that the threading head 4 nearest the cutting die 1 is fixed to the rails 4a, whereas the balance of the threading heads 60 are movable along these rails. Likewise, the fixed threading head does not have means for carrying the bracket 36.

Figures 19 and 20 show how the movable threading heads are mounted on the rails 4a. The bases of the heads each have two ribs 4b extending parallel and adjacent to the rails 4a to which T-shaped brackets 4c are secured. The cross arms of the brackets 4c carry at each end a roller 4d which rides on the rails 4a. The vertical arms of the brackets 4c extend below the rails 4a and carry a roller 4e which engages the bottom side of one of the rails 4a and prevents the head from tipping. The brackets 4c each also have a roller 4f adjacent one of the rollers 4d but turning on an axis at a right angle to the axis of the adjacent roller 4d so as to engage

the sides of the rails 4a and thus prevent the heads from moving forward or back on the rails.

Each threading head 4 guides a ladder tape 54 vertically upwards from a hamper 55 carried by each head and in which a quantity of ladder tapes cut to the length required for the blind being assembled but connected end to end with each other are stored. Each head guides a ladder tape to a point where a slat may be passed through the side tapes and the cross tapes of the ladder tape, and each head spreads the tape which it is guiding so that the slats can readily pass through the tapes.

After a slat has passed through all of the tapes which are required for a particular blind, each head inserts a needle with a lifting cord attached through a lifting cord hole corresponding to the tape being assembled by that head. The position of the slat (and therefore of the needle) is fixed relative to each threading head and since the cross tapes of a ladder tape are on alternate edges of the tape, the cross tapes must be fed through the head on alternate sides of the needle. This is accomplished by providing a single vertical passageway on the threading heads through which all of the cross tapes of the ladder tape pass. This passageway reciprocates in a path parallel to and beneath the slats so that the cross tapes are brought to the point of assembly with the cross tapes first on one side and then on the other side of the needle.

Each head carries guides for the slats so that the slats can readily pass from one head to the next from the cutting and punching section. Each head carries means for tilting these guides so as to release the slats in order to raise each slat after it has been passed through a ladder tape. Each head also carries means for lifting the slats after each slat has been passed through a tape. Raising a slat also raises the ladder tape (since the slat has been passed between a pair of cross tapes) and in this manner the ladder tapes are pulled through the threading heads. Finally, each head has slat supports which hold the slats and the tapes after they have been assembled above the assembly point.

A complete threading head is shown in Figures 19, 20 and 21, Figure 19 being a view of the left-hand side of a head (viewing Figure 1), Figure 20 being a front elevation and Figure 21 being a plan view. Each head comprises a casing made up of two castings 56 and 57 which carry the several operating parts which are required to carry out the functions just enumerated above.

Referring to Figure 20, each head has a block 58 having a vertical converging passageway 59 through which all of the cross tapes of the ladder tape pass. The block carries two divergent guide fingers 60 which form a lower extension to passageway 59 and assist in guiding the cross tapes through the passageway 59.

The block 58 also carries four tape spreaders 61 (two of which are shown in Figure 20) which press outwardly on the side tapes so as to provide a free passage for a slat through the tapes.

Two needle fingers 62 (see Figure 21) are mounted on mechanism later described to grasp a lifting cord needle 63, raise it out of one of two sockets formed in the block 58 to permit a slat to pass through the head and thereafter lower the needle into the other of the two sockets carried by the block 58 and, in so doing, pass the needle 63 through a hole for a lifting cord which has previously been punched in a slat. The upper end of the needle 63 carries one of the lifting cords of the blind being assembled so that when the slat is raised, the lifting cord is threaded through the lifting cord hole in the slat.

The block 58 reciprocates in a path parallel to the length of the slats being assembled so that first one and then the other socket in the block is directly beneath the needle and can hold the needle when the fingers 62 lower to place the needle in a socket. By this reciprocating motion of the block 58, the vertical guide 59 for the cross tapes is placed first on one side and then on the other side of the needle 63 to take care of the fact, pre-

viously noted, that in Venetian blind ladder tapes, the cross tapes are always on alternate sides of the side tapes.

The slats are fed from one threading head to the next through oval shaped guides 64. Since three of the threading heads are movable, the guides are made in short sections which telescope within each other. By mechanism hereinafter described, the slat guides are tilted outwardly so as to release the slats after they have passed through all the tapes being used for the particular blind being assembled. The point where the slats pass through the tape in each head is designated the assembly point and is designated by the letter P in the drawings.

Each head also has two slat lifters 65 which reciprocate vertically and raise the slats after they have passed through all of the ladder tapes with which they are being assembled. Since the slats have been threaded through the tapes, raising the slats also raises the tapes.

Each head also has two slat supports 5 which are in the form of two vertically extending arms spaced on each side of the slats a distance slightly more than the width of the slats. As appears in Figure 19, when the slat lifter 65 rises to lift a slat from the assembly point P, the slat and the cross tapes are pushed upwardly through the two arms of each slat support 5. Each arm has a spring-loaded latch 66 which is resiliently pressed toward the other arm and is pivoted at its lower end so that when a slat is raised between the two arms, the latches 66 are pressed outwardly to allow the slat to pass them. After the slat has passed, the latches then spring inwardly beneath the slat to hold it (and the tapes secured to it) above the assembly point P.

Each slat support 5 also provides two places where head rails for the Venetian blinds being assembled can be placed temporarily by the operator while lifting cords 35 carried by the head rail are secured to the lifting cord needle and while the side tapes of a ladder tape are secured to a tilt bar in the head rail. A forward arm of one of the two slat supports 5 for a threading head has a forwardly extending bracket 5a in which a head rail 40 can be placed while an operator secures a lifting cord to the lifting cord needle. These brackets 5a also hold a head rail when the movable die 3 and the movable threading heads are adjusted in accordance with the length of the head rail as heretofore described. The two arms of each slat support 5 also have shoulders 5b formed adjacent their upper ends. During the operation of my assembly machine, an operator places a head rail on the shoulders 5b while the side tapes of the ladder tapes in the heads are being secured to a tilt bar in the head rail.

Drive in the threading heads for the operating parts

Figures 22 through 30, inclusive, show the main parts of the drive for the several individual operating parts just referred to. All of the threading heads are driven by the common shaft 12. Each casting 56-57 carries in ball bearings 67 a shaft 68 which forms part of the common shaft 12. The shaft 68 carries a cam wheel 69 (see Figures 25-29, inclusive) which has several cam grooves cut on each side of its periphery. The right-hand side (viewing Figure 1) of the cam 69 has two cam grooves 70 and 71 and the left-hand side has one cam groove 72. The periphery of the cam 69 has two more cam grooves 73 and 74.

The cam grooves 70-74, inclusive, drive and control the several operating parts referred to above so that they act in the correct time sequence. This will be explained in connection with the description of each of the operating parts.

A double rack bar 75 mechanically connects the cam 70-74 with several operating parts; namely, the tape spreaders 61, the needle fingers 62 and the tilting mechanism for the slat guides 64. As appears in Figures 19, 21 and 22, this bar 75 reciprocates from front to back of the threading head in guides 76 secured to a top plate 77 for each head. A cam lever 78 pivoted at its lower end on a shaft

79 in the casting 56—57 has an arm 80 which carries a cam follower 81 moving in the groove 71 of the cam 69. The upper end of the lever 78 is forked and engages a short shaft 82 carried by an adjusting block 83 on the rear end of the rack bar 75. As appears from Figure 22, rotation of the cam 69 will pivot the lever 78 about its pivot point 79 and thereby cause the rack bar 75 to move from front to back of the head. The adjusting block 83 carries a bolt 84 which engages a stop 75a on the rack bar whereby the amount of horizontal position of the rack 75 can be adjusted.

The double rack bar 75 is shown in detail in Figures 30 and 31. At its forward end, it has two pinion racks 85 and 86, the rack 85 being higher than the rack 86. The forward end of the rack 75 also has laterally extending arms 87 which terminate in round pins 88. Each arm 87 also has a downwardly extending pin 89. As will be explained later, the racks 85 and 86 operate the needle fingers 62, the pins 88 tilt the guides 64, and the pins 89 operate the tape spreaders 61.

Ladder tape guide

The guide for the ladder tapes is shown in Figures 32, 33 and 34. As earlier described, it comprises the block 58 which is supported by two side plates 58a and which has the upwardly converging passageway 59 for the cross tapes. As appears in Figure 35, the side tapes are passed immediately in front and immediately behind the block 58, whereas all of the cross tapes pass through the passageway 59. An operator feeds a ladder tape by hand through and around the block 58 and secures the upper ends of the side tapes to a tilting bar in a head rail placed at the top of the slat supports 5 (see Figures 2 and 19).

Tape spreaders

As a slat passes from the cutting and punching section A through the threading heads and through the ladder tape carried by each head, it is important that the portions of the ladder tape above the block 58 be held apart so that the slats can pass easily through the tapes. Tape spreaders for this purpose are shown in Figures 35 to 38, inclusive. Two side plates 58a, which carry the block 58, also carry adjacent their ends four vertically journaled rods 90. Each rod 90 at its upper end carries a tape spreader in the form of a lever 61 which extends inwardly over the top of the block 58. Figure 36 shows the levers 61 in the open position when a tape can be threaded through the machine by an operator or when a slat and a tape are lifted from the point of assembly P. Figure 35 shows the levers 61 in the closed position in which they are pressing outwardly against the side tapes so as to insure clearance for the slats as they pass through the tapes.

The levers 61 on the rear of the block 58 have plate-like extensions 92 which have cam openings 93 cut therein. The pins 89 on the rack bar 75 extend downwardly through the cam openings 93 and forward and back movement of the rack bar 75 turns the levers 61 which are to the rear of the block 58. The rods 90, to which these levers are secured, carry at their lower ends beneath the side plates 58a, sector gears 94 which mesh with sector gears 95 (see Figure 38) fastened to the rods 90 which are to the front of the block 58. Rotation of the rods 90 to the rear of the block thereby rotates the levers 61 which are to the front of the block 58.

Needle fingers

The needle fingers 62 place the needle 63 through a hole in a slat for a lifting cord and into a socket (hereinafter described) in the block 58, whereupon the slat is raised. Before the slat is raised, however, the needle fingers must, of course, be moved away from the needle and out of the upward path of the slat. Thereafter, the fingers again grasp the needle and lift it out of the socket so that a slat can pass through the threading head, following which the needle is again placed in a hole in the next slat.

The needle fingers 62 and their driving mechanism are shown in Figures 21, 22, 39, 40 and 41. Referring to Figure 39, which shows the fingers in the closed position around the needle, each finger comprises an elongated member pivoted at one end and curved inwardly towards the opposite needle at the other end. Each free end of each finger has a small depression 96 formed in the surface of the finger facing the opposite finger. The depressions 96 are shaped so that together they match the cross-section of the needle. Each needle has in the center of the depression 96 a pin 97 which serves to grasp the needle when the fingers are closed, as will be herein-after described.

The fingers are pivoted about a vertical shaft 98 (see Figure 22) which is carried by the top plate 77 and a cap 99 secured to the top plate (see also Figure 21). At their pivoted ends, each finger 62 has a gear 100 and these gears mesh with the pinion racks 85 and 86 on the double rack bar 75. Forward and back movement of the bar 75, therefore, swings the fingers 62 between the closed position shown in Figure 39 and the open position shown in Figure 41.

As pointed out above, the needle, when grasped by the fingers 62, must be periodically raised and lowered. Figures 22, 23 and 24 show the mechanism for producing this motion. It is accomplished by raising and lowering the top plate 77 and all of the parts which that plate carries. A leg 101 extends down inside the casting 56—57 between the cam wheel 69 and the half 57 of the casting. It slides vertically in gibbs 102 secured to the casting 57 and has integral therewith flanges 103 and 104 to which the top plate 77 can be bolted. The lower end of leg 101 has a cam follower 105 which rides in the cam groove 70 in the cam wheel 69. Rotation of the cam 69 will raise and lower the top plate 77 and, therefore, the needle fingers 62 at the proper time.

Lifting cord needle and needle sockets

As heretofore noted, the block 58 has two sockets into which the lower end of the needle 63 is inserted and which support the needle. These sockets will now be described, reference being made to Figures 42, 43, 44 and 45. They are located on the top surface of the guide block 58. As shown in these figures, the sockets are generally hollow rectangles with projections extending inwardly from their sides and in the plane of their top surface. Thus, each socket has projections 108 extending inwardly at the corners from one side and a projection 109 extending inwardly from the central portion of the other side. These projections engage openings formed in the lower end of the needle 63, as will now be described.

The needle is shown in Figures 46, 47, 48A, 48B and 48C. It comprises two legs 110a and 110b made of two flat strips of resilient metal spaced from and parallel to each other by a block 111. At the upper end of the needle the block 111 is cut out so as to form a shoulder 111a and provide room between the legs for a spring-loaded lever 112 pivoted at 112a and carrying at its upper end an inwardly curved point 112b. The needle holds a lifting cord between the shoulder 111a and the point 112b. The lever 112 has a lower arm 112c which serves as a handle which can be depressed to swing the point 112b away from the shoulder 111a to thread a lifting cord into the needle or to release a lifting cord after a blind has been assembled.

The block 111 also extends only approximately two-thirds the length of the needle so that the two legs 110a and 110b can be pressed towards and away from each other to engage the sockets 106 or 107. As shown in Figures 46 and 47, the lower ends of the legs have a circular opening 113 into which the pin 97 (see Figure 39) on the ends of the fingers 62 fit when the fingers 62 are in the closed position and holding the needle. Below the opening 113, the leg 110a has two rectangular shaped notches 114 cut in from each edge and the leg 110b has

a rectangular opening 115 centered in the leg and on the same horizontal center line as the notches 114.

Figures 48A and 48B show how the sockets 106 and 107 engage the needle. In Figure 48A, the needle fingers 62 are in the closed position (see Figure 39) and have lowered the needle into one of the sockets 106 or 107. As appears in Figure 48A, the fingers 62 have pressed the legs 110a and 110b together so that the legs will clear the projections 108 and 109 (see Figure 42). The fingers 62 are opened, whereupon the legs 110a and 110b, being of resilient material, spring open to the position shown in Figure 48B. The notches 114 in the leg 110a slide over the projections 108 in the corners of the sockets 106 or 107 and the rectangular shaped opening 115 in leg 110b fits over the central projection 109 in the socket 106 or 107. The fingers then swing to the open position (see Figure 41) and the needle remains held by one of the sockets while the slat through which the needle has been passed is raised in the slat supports 5. Since a lifting cord is secured to the other end of the needle, this lifting cord is threaded through the slat.

Subsequently, the fingers 62 close the legs 110a and 110b together, as shown in Figure 48A, and raise the needle out of the socket 106 or 107. To be sure that the notches 114 or the opening 115 do not catch on the inwardly projecting portions 108 and 109 of the sockets when the needle is being lowered or raised in the sockets, I provide a block 116 on the inner face of the leg 110a which fits into the rectangular opening 115 in the leg 110b when the two legs are pressed together. For the same purpose, the leg 110b carries two rectangular blocks 117 which fit into the notches 114 in the leg 110a.

Thus, when the legs are compressed, the notches 114 and the rectangular opening 115 are filled by the blocks 116 and cannot catch on the projections 108 or 109.

As has been previously pointed out, the cross tapes on conventional ladder tapes alternate from side to side and, therefore, the block 58 with its passageway 59 for the cross tape is moved back and forth to place the cross tapes first on one side and then on the other side of the needle 63. It is for this reason that the block 58 carries two needle sockets 106 and 107 so that, irrespective of the position of the passageway 59, there will be a socket into which the needle 63 can be inserted.

The mechanism for reciprocating the block 58 is shown in Figures 27, 28, 29, 32, 34 and 34A. A block 118 (see Figures 32 and 34) integral with the side plates 58a supports the block 58 and its associated parts. The block 118 slides on horizontally extending slide plates 119 which are bolted to the castings 56—57. The block 118 carries a centrally positioned vertically extending pin 120 which extends beyond the top and bottom of the block 118 into grooves 121 cut in the slide plates 119. A cam lever 122 pivoted about a shaft 123 has a fork 124 at one end which extends through a slot 125 in the block 118 around a roller 126 rotating on the pin 120. The other end of the lever 122 has a cam follower 127 which rides alternately in the grooves 73 and 74 in the periphery of the cam 69 (see Figure 28). As is apparent from Figure 34, the block 118 (and therefore the block 58) will reciprocate horizontally as the cam follower 127 moves from the cam groove 73 to the cam groove 74 in the cam 69 or back again.

Figures 28 and 29 show the mechanism whereby the cam follower 127 is caused to swing from the cam groove 73 to the cam groove 74 and back again. A portion of the cam wheel between the two grooves 73 and 74 is replaced by a gate 128. This gate has a shaft 129 which turns in a radially extending socket 130 in the cam wheel 69. A pin 129a extending through the cam wheel and a groove 129b holds the gate in the wheel. The gate 128 has two portions extending beyond the shaft 129 and across the cam grooves 73 and 74. One portion 131 is relatively short and crosses one of the cam grooves abruptly, its edge forming a large angle with the sides of the

cam grooves. The other portion 132 is long and when extending across the cam grooves forms a relatively small angle with their sides.

The operation of the gate 128 will now be described with respect to Figure 28. Assuming that the cam follower 127 is in the cam groove 73, upon rotation of the cam wheel 69 in the direction of the arrow in Figure 28, the cam follower 127 will strike the long end 132 of the gate and be deflected thereby into the cam groove 74 where it will strike the short end 131 of the gate. This will turn the gate 128 into the position shown in chain lines in Figure 28. The cam follower 127 will continue in the cam groove 74 until it strikes the long end 132 of the gate which now extends across the cam groove 74, whereupon the cam follower 127 will be deflected into the cam groove 73, hit the short end 131 of the gate and flip gate 128 back to the position shown in solid lines in Figure 28. A spring-loaded pin 133 in the cam wheel 69 presses into notches 134 cut in the shaft 129 to hold the gate in the two positions shown in Figure 28.

Slat guides and mechanism for tilting them

As previously described, the slats are led from one threading head to the other through slat guides 64 carried by the heads. These guides must be tilted to release the slats so that they can be raised in the slat supports 5. The guides 64 and their operating mechanism are shown in Figures 20, 49, 50, 51, 52, 53 and 54.

The guides themselves are shown in Figures 53 and 54. They are in the form of oval-shaped tubing with a longitudinal slot 135 extending its full length. As shown in Figures 50 and 51, the edges of the slats pass through this slot and thereby the slats are guided. Since the distance between the threading heads varies in accordance with the width of the blind being assembled, the guides are made up of a series of short sections 64a, 64b and 64c which are tapered to telescope one within the other and the slot 135 is widened at the leading end of each section to facilitate passage of the slats from section to section through the guides. The end sections of each guide are carried in plates 136 and 137 which are mounted in the arms of the slat supports 5 on pivots 138 (see Figure 49).

In order to release the slats from the guides, the plates 136 and 137 are rotated about their pivots 138 from the position shown in Figure 51 to the position shown in Figure 52. This motion is timed and operated by the double rack bar 75, the pins 88 of which (see Figures 30 and 31) pass through slots 139 in the plates 137. The slots 139 are formed in the plates 137 as shown in Figure 52 so that forward and backward movement of the double rack bar 75 will rotate the plates 137 about their pivots 138. The ends of the plates 136 and 137 adjacent the pivot points 138 are in the form of sector gears 140 which mesh with each other so that rotation of a plate 55 137 about its pivot point 138 will rotate the mating plate 136 about its pivot point 138.

Slat lifting mechanism

As above indicated, after slats have been passed through the ladder tapes at the assembly point P and after needles carrying lifting cords have been inserted in the lifting cord holes in the slats, the slats are raised. Figures 55, 56 and 57 show the mechanism for raising the slats. Each threading head carries two slat lifters 65 (see also Figure 20) which are moved upwardly to engage the bottom side of the slats and lift them between the two arms of the slat support 5 until they are engaged by the latches 66 (see Figure 50). The two lifters 65 have a common base 141 which has vertically extending holes 142 by which it rides on two vertically extending bars 143. The upper ends of the bars 143 are supported by the bottom slide plate 119 for the block 118 (see Figure 32). The bars are supported at the bottom by a flange 144 extending forwardly and upwardly from the cross arm of the T-shaped bracket 4c secured to the front rib

4b on the base of the threading head. A cam lever 145 pivoted at one end about a shaft 79 (on which the lever 78 also pivots, see Figure 22) raises and lowers the common base 141. The free end of the lever 145 has a yoke 146 which extends around a roller 147 carried by the base 141. The lever 145 has a cam follower 148 adjacent its central portion, which cam follower runs in the cam groove 72 in the cam wheel 69. As is apparent from Figure 56, rotation of the cam wheel 69 will raise and lower the slat lifter 65 at the proper time in the operation of my machine.

Tape lock and operating mechanism therefor

While a slat is being passed through a ladder tape in a threading head, it is obviously important that only one cross tape be beneath the slat at the assembly point P and be free to rise with the slat when the slat is raised. I provide a tape lock which blocks the passageway 59 for the cross tapes and permits only one cross tape at a time to pass out of the passageway 59. The tape lock and the operating mechanism therefor is shown in Figures 58, 59, 60, 61 and 62.

The tape lock is a U-shaped plate 149 (see Figure 58), the legs of which extend along the sides of the socket 106 and slide in grooves 150 formed in the side walls of the socket (see Figure 43). As shown in Figure 59, the lock 149 normally extends across passageway 59 being held in that position by a leaf spring 151 which is carried in the block 58. It is moved to the open position shown in Figure 60 by a crank lever 152 which is pivoted at 152a on one of the side plates 58a of the block 58. One arm of the lever 152 has a vertical pin 153 which extends upwardly through a slot 154 in the tape lock 149. The other arm of the crank lever 152 carries a roller 155, which, on movement of the block 58, engages a pin 156 carried by a rod 157 extending from the top of the threading head. When the block 58 moves sidewise in order to place one or the other of the needle sockets under the lifting cord needle 63, the roller 155 hits the pin 156 so as to always turn the lever 152 clockwise (viewing Figure 61). This moves the lock 149 to the left against the spring 151 to the position shown in Figures 60 and 61.

The lock is held in the open position by a latch 158. This latch is a U-shaped member (see Figure 58) which is hinged to the lock 149 by means of hinge leaves 159 and hinge pin 160 (see Figure 62). The latch 158 is resiliently held in a position parallel to the lock 149 by a spring 161. When the lock 149 closes the passageway 59, the latch 158 is in the position shown in Figure 59. When the lock is moved to the left to clear the passageway 59, the latch 158, because of the spring 161, moves downwardly to the position shown in Figure 60. The spring 151 tends to press the lock 149 to close the passageway 59 but the legs of the latch 158 are against the needle socket 107 and prevent the lock 149 from closing the passageway 59. A cross tape can then be pulled up through the passageway past the lock 149.

As the cross tape continues its upward motion, it strikes the latch 158 and lifts it away from the socket 107, whereupon the spring 151 moves the lock 149 to the right (viewing Figure 59) to again close the passageway 59.

Main drive

The main drive for my machine is housed at the right-hand end of my machine in a cabinet 162 (see Figure 1). This drive turns the shaft 12 which operates each of the threading heads 4 and the dies 1 and 2. It also drives the die 3 when blinds with two tapes are being assembled. This drive may also operate the blind conveying section C.

This drive is shown in Figures 9 and 9A. It comprises a main motor 163 connected by a belt drive 164 to a shaft 165 which carries a pinion 166 meshing with a larger pinion 167 which turns on but is not keyed to

the shaft 12. The pinion 167 drives the shaft 12 through a conventional dog clutch 168 which has two stops. One stop is operated by a solenoid 169 and the other stop is operated by a cable 170 which leads to a hand lever 171 mounted on the front of the cabinet 17 (see Figure 1). In a conventional dog clutch, there is, as in all clutches, a driving member and a driven member. A pin or dog spaced from the axis of the driving member and carried by the driving member is movable axially so as to extend into a slot extending axially in the driven member whenever the dog and the slot are in alignment. The dog is spring loaded so as to urge it into the slot in the driven member. The clutch has a lever which engages the dog to withdraw it from the slot in the driven member. The solenoid 169 and the cable 170 operate two dog levers positioned 180° apart which in turn actuate a dog in the clutch 168.

The dog lever, operated by the solenoid 169, is normally in position to engage the dog and thereby disengage the clutch. When the solenoid is energized, it momentarily withdraws the dog lever out of engagement with the dog. The clutch is engaged and turns the shaft 12 through one complete revolution, at which point the dog lever again engages the dog and disengages the clutch.

The dog lever, operated by the cable 170, is normally positioned out of engagement with the dog so that the clutch remains engaged. When the cable 170 is pulled, it moves its dog lever into engagement with the dog, disengages the clutch and stops the shaft 12.

The pinion 167 and another pinion 172 rotate freely on the shaft 12 by virtue of a hollow shaft 173 which carries these two pinions on the shaft 12 (see Figure 9A). The outer end of the shaft 12 beyond the clutch 168 carries a pinion 174. The pinions 172 and 174 drive the blind conveying mechanism, as will be hereinafter described. All of the shafts are held by suitable supports 175 within the cabinet 162.

The machine is designed so that, during one revolution of the shaft 12, a full cycle operation is performed in the cutting and punching section A and in the assembly section B. The crank 20 on the shaft 12, which drives the cutting and punching section and the cam wheel 69 for each of the threading heads 4, are positioned on the shaft 12 so that all the actions of the cutting and punching section and of the assembly section occur in timed sequence during this one complete revolution. In other words, during one revolution, the dies in section A are raised and lowered to cut and punch a slat and, in the assembly section B, the lifting cords are threaded into another slat and that slat is raised up away from the assembly point P in each threading head; also, the lifting cord needles are raised and the ladder tapes are spread for the next slat to pass through the threading heads.

The rotation of the shaft 12 for the one complete revolution, during which all of the operations just described are performed, is controlled by the solenoid 169 actuating the dog clutch 168. In other words, when the solenoid 169 withdraws the usual dog clutch lever to engage the clutch, this action initiates the one complete revolution. When the shaft 12 has completed this revolution, it is stopped by the lever controlled by the solenoid 169 which lever has returned to its position to throw the clutch out of engagement.

As above noted, the stop, actuated by the cable 170, is spaced 180° from the stop controlled by the solenoid 169. When the cable is manually operated, therefore, it stops the shaft 12 after it has completed one-half of a revolution. At this point, the cord needle 63 is in one of the sockets 106 or 107, the needle fingers 62 are open, the tape spreaders are withdrawn inwardly, and the dies in section A are down. Although the feeding rollers 13 continue to run, no slats can pass into the assembly section B because the slats are stopped by the dies. At this half revolution position, therefore, the operator can readily secure lifting cords which are carried by the head

rails of the blinds being assembled to the lifting cord needles, and also secure the ladder tapes to the tilt bars in the head rails.

Control for the main power drive

Rotation of the main shaft 12 is controlled by the position of a slat in the assembly section B. In connection with the description of the length adjustment mechanism, it was explained that the number of threading heads used in any one operation depended on the number of tapes being assembled and further, that the bracket 36 (see Figures 12, 13 and 14) was secured to that threading head of those being used which was farthest removed from the cutting die 1. The bracket 36 also carries a microswitch 176 which is positioned so that it will be hit by the forward end of a slat which is passed through the threading head to which the bracket 36 is attached. Closing the microswitch 176 actuates the solenoid 169, which, as explained above, engages the dog clutch 168 and permits the shaft 12 to complete one full revolution.

In the description of the cutting and punching section, I also pointed out that, whenever a blind was being assembled which had more than two holes for lifting cords, it was necessary to use the die 3, the operation of which is controlled by the dog clutch 25 (see Figure 9). In order to actuate the die 3 at the proper time, I provide a solenoid 177 which operates the dog clutch 25 and which, in turn, is controlled by microswitches 178 carried by the threading head or heads which are between the fixed threading head and the last threading head which is being used in any given operation. As will be later described, these microswitches 178 have operating levers which can be positioned so that they are in the path of the slats as they move through the threading heads and be actuated by the forward end of the slats. When a slat strikes the operating lever for one of the microswitches 178, it energizes the solenoid 177, which in turn operates the dog clutch 25 and thus the punching die 3. The drive for the punch 3 also actuates mechanism (hereinafter described) to move the operating lever of the microswitch out of the path of the slat so that the slat can continue through to the next microswitch 178 carried on the next threading head and, finally, through the last threading head where it strikes the microswitch 176 which, as explained, actuates the solenoid 169 and thereby causes the shaft 12 to turn one full revolution.

The operating levers for the microswitches 178 and the mechanism for withdrawing the levers out of the path of the slats will now be described with reference to Figures 63-66, inclusive. The microswitches 178 are carried on a bracket 179 secured to the left-hand side of the intermediate threading heads (viewing Figure 1). These switches are located below the path of travel of the slats. A post 180, also mounted on the bracket 179, has a two-way pivot 181 for an L-shaped lever 182. When the microswitch 178 is to be actuated by the leading end of a slat, the lever 182 is in the position shown in solid lines in Figure 64 in which the long leg of the L-shaped lever is horizontal and the short leg of the lever is vertical. The lower portion of the short leg is against the microswitch and the upper portion is in the path of travel of slats through the threading heads. When a slat strikes the lever 182, it tilts the lever about a vertical shaft 183 in the pivot 181 and the lower portion of the short leg of lever 182 momentarily closes the microswitch 178. A spring-loaded ball 184, also mounted on the bracket 179 adjacent to the switch 178, assists the spring in the microswitch to move the lever 182 back away from the microswitch to open the switch. A stop plate 185 mounted on the side of the post 180 limits the amount which lever 182 rotates under the pressure of the spring-loaded ball 184. As appears in Figure 63, the lever 182 carries a hardened plate 186 which the ends of the slats strike when they come against the lever 182.

As appears in Figures 63 and 64, the lever 182 is pivoted at a point on its longer leg so that a sufficient amount of the longer leg extends beyond the pivot point on the side opposite the short leg to overbalance the short leg and keep the lever with its longer leg in a generally horizontal position and with the short leg in the path of the slats. In order to get the short leg of the lever 182 out of the path of the slats at the required time, the lever 182 is tilted by another lever 187. The lever 187 is pivoted on the casting 56 at 188 and when turned counterclockwise (viewing Figure 64) its arm forward of the pivot 188 rises and strikes a pin 189 carried by the lever 182 in its longer leg and rearward of the pivot 181.

15 The drive for the punch 3 tilts the lever 187, as will now be described. Referring to Figures 9 and 11, it will be seen that the crank 27 which carries the crank lever 28, which actuates the die 3, is in the form of a cam. Rotation of this cam raises and lowers a cam lever 190 which turns a shaft 191 to which it is connected through the levers 192 and 193. The shaft 191, which extends the full length of the assembly section B and at the rear of the several threading heads, carries crank levers 192 at positions to the rear of each of the levers 187. As shown in Figures 63 and 64, the rear arms of the levers 187 are pivotally connected to the crank levers 192.

As heretofore explained, when one of the microswitches 178 is struck by the leading end of a slat, it energizes the solenoid 177 which in turn actuates the dog clutch 25 and starts the drive for the punch 3. Crank 27, as part of the drive, turns and through the cam lever 190 and the levers 192 and 193 turns the shaft 191. Rotation of the crank 27 turns the shaft 191 clockwise (viewing Figure 64) tilting the lever 187 counterclockwise about the pivot 188. The forward arm of lever 187 strikes the pin 189 on the lever 182, raises the long leg of the lever 182 and lowers the short leg of the lever 182 thereby moving it out of the path of the slats.

When one or both of the intermediate heads are not required for assembling a particular width blind, it is necessary to hold the operating levers 182 out of the path of the slats. Accordingly, I provide a set screw 181a, threaded into the base 181b of the pivot 181 and which can be turned against one of the horizontal pivot arms 181c (see Figure 66). When one or both of the operating levers 182 on the intermediate heads are to be held out of the path of the slats, the lever is tilted to the position shown in chain lines in Figure 64 and the screw 181a is turned in against the pivot arms 181c to prevent the lever from returning to its normal position.

Sequence of operation

Figure 67 shows diagrammatically the sequence of operation of the microswitches 176 and 178, the threading heads 4 and the cutting and punching dies 1, 2 and 3. In this figure, the four threading heads have been marked A, B, C and D for reference. The slat lengths included within the bracket I show the sequence for a two tape blind. The three slat lengths within the bracket II show the sequence for a three tape blind which, however, has only two lifting cords, and the four slat lengths within the bracket III show the sequence for a four tape four lifting cord blind.

In order to make a two tape blind, the operating shafts 23 and 30 are first connected together by means of the lock 31 (see Figure 9). A length of slat material 194 is then fed through the feed rollers 13 and the dies 1, 2 and 3 until a short end projects beyond the cutting die 1. The microswitch 176, which, when a two tape blind is being made, is carried on the threading head B, is then tripped by hand to actuate the solenoid 169. The shaft 12 turns and all of the dies are actuated, thus trimming the front end of the slat and cutting lifting cord holes 195 and 196. The motor 16 is started and the slat material 194 is fed by the rollers 13 through the

threading heads A and B until its leading end hits the microswitch 176. This again actuates the dies 1, 2 and 3. The die 1 again cuts the slat material 194 to form the rear end of a finished slat 194a and the front end of a succeeding slat 197, and the dies 2 and 3 cut lifting cord holes 198 and 199 in slat 197.

While the dies are forming the slat 197 (except for cutting the rear edge), the slat 194a is being processed by the threading heads A and B. When the slat 194a struck the microswitch 176, it had passed through two ladder tapes held in place by the threading heads A and B. Thereafter, and while the dies are operating on slat 197, a lifting cord needle has been inserted in each of the holes 195 and 196 and the slat 194a has been raised up in the slat supports 5 together with ladder tapes in the heads A and B to make way for the slat 197 which will be fed through the heads A and B by the rollers 13 as soon as the dies 1, 2 and 3 raise.

To make a slat for a blind having three lifting cord tapes (which normally has only two lifting cords), three threading heads A, B and C are used. The microswitch 176 is placed beyond the threading head C and one of the microswitches 178 is brought into position on the threading head B. The operating shafts 23 and 30 for the dies are disconnected mechanically from each other (see Figure 9) and a length of slat material 198a is fed by hand through the dies 1, 2 and 3 until a short length extends beyond the cutting die 1. The microswitch 176, now on the threading head C, is tripped by hand and this action operates the die 1 which cuts the front end of the slat material 198a and the die 2 which punches one lifting cord hole 199a in the slat. The motor 16 for the feed rollers 13 is started and the material 198a is fed through the threading head A until it strikes the operating lever for the microswitch 178 on the threading head B. Tripping the microswitch 178 actuates the solenoid 177 which controls the dog clutch 25, whereby the die 3 is actuated to cut a second lift cord hole 200 in the slat material 198a. As described above, when the cam crank 27 turns to operate the punch die 3, it also tilts the operating lever for the microswitch 178 out of the path of the slat. The feed rollers 13 then pass the slat material 198a through the threading heads B and C until its leading ends strike the microswitch 176. Tripping the microswitch 176 cuts the material 198a to complete a slat 198b and form the front end of a succeeding slat 201 and also punch a lifting cord hole 202. During this operation the slats 198b is being processed by the threading heads A, B and C in the same manner as slat 194a was processed.

To make a four tape blind with four lifting cords, all four threading heads A, B, C and D are used, the microswitch 176 is placed on the last threading head D, and two microswitches 178 are placed one on each of the threading heads B and C in advance of these threading heads. The drive shafts 23 and 30 for the cutting dies (see Figure 9) are mechanically disconnected from each other, but the solenoids 169 and 177 are connected into the same electrical circuit with the microswitch 176 so that when this switch is tripped, the die 3 will operate with the dies 1 and 2. A length of slat material 203 is fed by hand through the dies 1, 2 and 3 and the microswitch 176 on the threading head D is tripped by hand. This trims the leading end of the slat and cuts lifting cord holes 204 and 205. The feed rollers 13 are then started and they feed the slat material 203 through the threading head A until it strikes the microswitch 178 which is on the threading head B. Tripping this microswitch operates the die 3 to cut hole 206. As described above, the drive for the die 3 also takes the operating lever for the microswitch 178 out of the path of the slat material which the feed rollers 13 then feed through the threading head B until the front end of the slat material strikes the microswitch 178 on the threading head C. The cutting die 3 is again operated to cut a hole 207 in the slat. The operat-

ing lever 178 on the threading head C withdraws and the feed rollers 13 pass the slat material through the threading heads C and D until its forward end strikes the microswitch 176 which actuates the dies 1, 2 and 3. The die 1 cuts the slat material to form the rear end of a completed slat 203a to form the forward end of the succeeding slat 208. The dies 2 and 3 cut holes 209 and 210 in slat 203. During this operation, the slat 203a is being processed by the threading heads A, B, C and D.

Figure 68 shows the electrical circuit for the microswitches 176 and 178 and the solenoids 169 and 177, whereby the sequence of operations just described can be accomplished. The circuit includes a source of electric current 211, overload circuit breakers 212 and a switch 213 which controls the microswitch circuit. The circuit also includes a relay 214 which actuates two pairs of contacts 215 and 216. When the switch 213 is closed and the microswitch 176 is tripped, it completes a circuit through the relay 214 which closes the contacts 215 to actuate the solenoid 169. This starts the main drive shaft 12 through one complete revolution.

If the die 3 is to be operated at the same time as the dies 1 and 2 when the microswitch 176 is tripped, a toggle switch 217 is closed manually. When the relay 214 closes the contacts 215, it also closes the contacts 216 which completes a circuit through the solenoid 177 which actuates the dog clutch 25 for the cutting die 3.

Figure 68 also shows the circuit whereby the cutting die 3 can be operated independently of the cutting dies 1 and 2 by the closing of one of the microswitches 178. As there shown, the switches are in parallel with each other but in series with the solenoid 177 and the source of power. Closing of either of the switches 178 will complete a circuit through the solenoid 177, energize it and thereby actuate the die 3 through the dog clutch 25.

Figure 68 also shows a control for the motor 16 which drives the feed rollers 13 and the dog clutch 25. A switch 218 is in series with the field of the motor 16 and closing or opening this switch starts or stops the motor 16.

The switches 213, 217 and 218 are all conventional toggle switches which, for convenience, are carried in the switch panel 17a on the front of the cabinet 17. As appears in Figure 9, a toggle switch can also be mounted in this switch panel to control the motor 163.

Blind conveying section

The blind conveying section has heretofore been generally described with particular reference to Figures 1, 3 and 4. The sprocket wheels 11, which carry the endless chains 6 and 7, are themselves carried by a rectangular frame work made up of vertical posts 219 and cross bars 220. A chain drive, including sprocket wheels 221 and 222, drives the endless chain 7, as appears in Figure 4. A shaft 223 extending across the top of the frame and supported at its ends by the cross bars 220 drives the chain 6 from the chain 7. Thus it will be noted from Figures 3 and 4 that the shaft 223 carries sprockets 224 at each end and these sprocket wheels engage the chains 6 and 7.

The main power drive in the cabinet 162 (see Figure 1) drives the conveyor section. Referring now to Figure 9, a shaft 225 carries the sprocket wheel 221 which, as just described, drives the endless chains 6 and 7. The shaft 225 carries a double clutch 226 which is slidable on the shaft 225 and carries clutch teeth 227 on one end and a clutch disc 228 on the other end. The clutch teeth 227 mesh with clutch teeth formed in a collar 229 which is secured to the shaft 225 together with a pinion 230. The pinion 230 meshes with the pinion 174. The shaft 225 also carries a sleeve 231 which at one end has a clutch disc 232 which can be engaged by the clutch disc 228. The sleeve 231 has at its other end a pinion 233 which meshes with the pinion 172.

A hand lever 235 positioned on the front of the cabinet 17 is used to operate the clutch 226 through a flexible

cable 234. When the clutch 226 is slid on the shaft 225 to engage the gear teeth 227, the chains of the conveyor section are indexed with the blind assembly section B in that the chains are moved only when the shaft 12 moves. Thus, rotation of the shaft 12 turns the pinion 174, the pinion 230 and the clutch 226 which rotates the shaft 225 carrying the sprocket wheel 221. When the clutch 226 is slid on the shaft 225 so that the clutch discs 228 and 232 engage, the conveyor section can be driven independently of the assembly section. Referring to Figures 9 and 9A, it will be seen that the pinion 166 turns the pinion 167 and the pinion 172. This turns the pinion 233 meshing with the pinion 172 and turns the clutch 226 and thereby the shaft 225.

Alternatively (as shown diagrammatically in Figure 15 4A), the blind conveying section can be driven by a separate motor 236 through a gear reducer 236a and a shaft 236b carrying the sprocket wheel 221.

The operation of the blind conveying section has also been generally described. Briefly, the cross bars 9 with the brackets 10 are brought to a position close to and above the slat supports 5. After ladder tapes have been secured to the tilt bar of a head rail and after the lifting cords which have been threaded through a conventional cord lock in the head rail have been attached at one of their ends to the lifting cord needles 63, the conveying section is started and the head rail is lifted, together with the tapes and slats as they are assembled. As just described, the motion of the conveying section may be indexed with the assembly section or the conveying section can be driven separately from the assembly section.

During the time that a blind is being assembled, the lifting cords carried by the head rail remain secured at one end to the lifting cord needles. It is, therefore, necessary to supply additional lengths of lifting cord through the head rail as the blind is assembled and carried away from the needles. This means that the conventional cord lock in the head rail must be kept open. I provide in the conveyor section a hook to hold the free ends of the lifting cords at an angle to the head rail, while the head rail is being raised, so as to hold the cord lock open. The action of the hooks is similar to the action of a person raising or lowering a finished blind installed in a window in which, to raise or lower a Venetian blind, the lifting cords are pulled at an angle to the head rail to release the cord lock.

Figures 69, 70, 71 and 72 show the hook and the operating mechanism therefor. They also show the manner in which the cross bars 8 and 9 are secured to the endless chains 6 and 7. Caps 237 at each end of the cross bars 8 and 9 are secured to the endless chains by pin 238 which take the place of two of the conventional chain pins in the chains 6 and 7. The caps 237 have bearings 239 so that the cross bars 8 and 9 can freely turn in the caps.

The bracket 10 which holds one end of a head rail has a downwardly and outwardly extending bracket 240 which carries a hook 241. The hook 241 is U-shaped and at the end of one of the legs of the U has a shaft 242 at right angles to the general plane of the hook and which is carried in a vertical position by the bracket 240. The shaft 242 always remains in a generally vertical position since the cross bars 8 can rotate freely in the end caps 237 and the weight of a head rail in the brackets 10 will tend to keep the brackets 10 directly below the cross bars 8.

The end of the leg of the U-shaped hook 241, which has the shaft 242, also carries a horizontally and outwardly extending lever 243 (see Figure 71). During movement of the conveyor section, the lever 243 strikes a cam 244 (see Figures 3 and 72) and the cam 244 rotates the hook in the bracket 240. During continued movement of the conveying section, the lever 243 clears the cam 244, whereupon a coil spring 245 on the shaft 75

242, secured at one end to the shaft 242 and at the other end to the bracket 240, snaps the hook 241 back to the position shown in Figure 71.

The action of the hook is as follows. Immediately after a head rail is placed on the bracket 10, adjacent the slat supports 5, those portions of the lifting cords which normally hang free from the cord lock and are used to raise and lower the blind are looped in the hook 241 (see Figures 1 and 71). As appears in Figure 1, this holds the cords at an angle to the head rail so that the cord locks are open and the lifting cords can be pulled through the lock as the head rail is raised. When the lever 243 is deflected by the cam 244 and then snapped back by the spring 245, the cords are thrown free of the hook so that an operator at the rear of the machine (viewing Figure 1) can use the lifting cords to raise and close the blind and prepare it for assembly.

When the conveying section is moving, there are four positions at which the cross bars 8 or 9 must be stopped in order to permit the operator to carry on certain manual operations. These four positions are indicated by the letters E, F, G and H in Figure 3. At the position E, head rails are placed in the brackets 10 as previously described. At the position F, the ladder tapes of the completed blind must be disconnected from the ladder tapes for the succeeding blind and the ends of the portions of the lifting cords which have been threaded through the slats must be released from the lifting cord needles. At the position G, which is immediately after the lifting cords have been released by the hook 241, operators at the rear of the machine fasten bottom rails to the ends of the lifting cords which had been held by the needles. They also secure the lower ends of the ladder tapes to the bottom rails. While a completed blind is moving from position G to position H, an operator pulls on the lifting cords to raise and close the blind. At the position H, the completed blind fully assembled and closed is removed from the brackets 10 for packaging.

As heretofore described, the conveying section is driven by the main drive in the cabinet 162. The movement of the conveyor is controlled by the operator by means of the hand lever 235 which operates the clutch 226. The conveyor can be stopped by throwing the clutch 226 in the neutral position. It can be indexed to move as the assembly section moves or it can be driven independently of the assembly section. With this arrangement, it is necessary for the operator to stop the conveyor section at each of the assembly points E, F, G and H. If, however, the conveying section is driven by a separate motor (as illustrated in Figure 4A) means can be provided to stop the conveying section automatically at the desired positions. A microswitch 246 can be placed on the vertical posts 219 adjacent the position E and a second microswitch 247 can be placed on this post adjacent the position F. Each of the microswitches has an operating lever 248. The switches are normally closed and are opened when a lever 249 projecting inwardly from one of the brackets 10 strikes the operating levers 248. This will open the circuit to the separate motor drive 236 for the conveying section and stop a cross bar 8 or 9 at the position E and at the position F. When a bar stops at position E, the other bar will stop at position G and when a bar stops at position F, the other bar will stop at position H. When manual operations have been completed at the positions E, F, G and H, an operator pushes a button to start the conveying section again.

Figure 73 shows the electrical circuit for the automatic operation just described. As shown, the circuit includes a main switch 250 which controls the entire circuit. This switch may be a toggle switch in the switch panel 17a in front of the cabinet 17 (see Figure 1). The microswitches 246 and 247 are in series with the motor 236. These switches are normally closed and opening

either one will obviously stop the motor 236. A manual push button 251 can be momentarily closed by an operator to start up independently of the microswitches 246 and 247. This will clear the microswitches 246 and 247 as indicated in dot and dash lines in Figure 73, whereupon they, being normally closed, will take over the circuit until one of them is again opened by the lever 249 striking an operating lever 248 on the switches.

Method of preparing ladder tapes

It has previously been stated that the ladder tapes are each cut to the required length before they are threaded through the threading heads, but that these cut lengths are fastened end to end and stored in the hampers 55 so that the tapes, although cut to length, can be pulled through the threading heads continuously. In Figures 74 to 80, inclusive, I show a method for preparing the tapes whereby they may be cut to the required length and connected end to end by the same operation. A side elevation of a conventional ladder tape is shown in Figure 74. It has two side tapes 252 and cross tapes 253. The first step in my method is to cut out several cross tapes (generally four, as shown in Figure 75). Loops are then formed from the portions of the side tapes from which the cross tapes have been removed, these loops having open ends 254, closed ends 255 and sides 256.

The next step is to staple together two sides 256 of the loops adjacent their open ends, as shown at 257 in Figure 77. Preferably, a short strip of cloth 258, which can be one of the cross tapes cut out in the first step, is stapled on the outside of one of the sides 256 at the same time the side tapes are stapled at the point 257. As shown in Figure 78, the strips 258 extend transversely of the side tapes forming the loop and preferably extend slightly beyond the edges of these side tapes. The sides 256 of the loops are also stapled together at a point between the closed ends 255 and the point 257, for example, at the point 259, as shown in Figure 77. The next step is to cut one of the sides 256 in a portion between the points where the two side tapes have been stapled together, as shown in Figure 79.

This completes the preparation of the tapes, as shown in Figure 79. The ladder tape is now in two portions 260 and 261 held together only by the staples at the points 257. The ladder tapes are stored in the hampers 55 in this condition. After a blind has been assembled and the head rail is in the position B (see Figure 3), an operator has only to pull the tapes 258 which will pull out the staples at the point 257, thus separating the two sections 260 and 261, as shown in Figure 80. In Figure 80, the section 260 shows the lower end of a cross tape in a blind which has been assembled and the section 261 is the forward end of a cross tape which has been pulled through a threading head. It will be noted that the section 261 has loops 262 already formed which can be secured to a tilting bar of the head rail of the blind next to be assembled.

The foregoing description demonstrates that I have provided a machine which will assemble the slats and ladder tapes of Venetian blinds and thread lifting cords through the slats and the ladder tapes. The machine is almost wholly automatic and requires only four or five operators to do the work which has heretofore been done by 15 to 20 workers. My machine greatly reduces the cost of assembling Venetian blinds, because heretofore assembling Venetian blinds has been entirely a manual operation. As heretofore stated, I estimate that my machine will reduce the cost of assembly lines approximately 80 to 85%.

While I have described certain present preferred embodiments of my invention, it is to be understood that they may otherwise be variously embodied within the scope of the following claims.

I claim:

1. A machine for assembling slats, ladder tapes and lifting cords of Venetian blinds comprising a die in fixed position for cutting the ends of slats, a second die for punching a hole for a lifting cord in said slat, said second die being spaced a fixed distance from the first die, a third die for cutting additional lift cord holes in said slat, said third die being movable in relation to the first two dies, threading heads for guiding ladder tapes to points of assembly of the tapes with slats which have been cut and punched, the threading head nearest the dies being fixed in position, the other heads being movable towards and away from the fixed head, means for feeding slats in long lengths through the dies and the side and cross tapes of the ladder tapes in the threading heads, a common operating drive for all of the threading heads and for the fixed dies, and a separate operating drive for the movable die, and means actuated by movement of the slats through the threading heads to control both drives.
2. A machine as described in claim 1 in which the fixed dies have a common operating shaft and the movable die has a separate operating shaft and means for connecting the two shafts together whereby the drive for the two fixed dies may optionally drive the movable die.
3. A machine for assembling slats, ladder tapes and lifting cords of Venetian blinds comprising dies for cutting slats from long lengths of slat material and punching holes therein for lifting cords, threading heads for guiding ladder tapes to points of assembly, for threading slats through the side and cross tapes of the ladder tapes at said points and for threading the lifting cords through the slats, means for feeding the slats through the dies and through the threading heads, an operating drive for said threading heads and for some of said dies, and a switch mounted on the threading head operating farthest from the dies, said switch being actuated by movement of a slat through said threading head and controlling said drive, said drive starting when the switch is closed by the slat, and means for actuating the balance of the dies when slats for blinds having more than two tapes are desired.
4. A machine for assembling slats, ladder tapes and lifting cords of Venetian blinds comprising dies for cutting slats from long lengths of slat material and punching holes therein for lifting cords, threading heads for guiding ladder tapes to points of assembly, for threading slats through the side and cross tapes of the ladder tapes at said points and for threading the lifting cords through the slats, means for feeding the slats through the dies and through the threading heads, an operating drive for said threading heads and for some of said dies, a separate drive for the balance of said dies, a switch mounted on the threading head operating farthest from the dies, said switch being actuated by movement of a slat through said head and controlling both drives, and switches carried by other heads and adapted to be moved into the path of the slats whereby they may be actuated, the second mentioned switches controlling said separate drive.
5. A machine as described in claim 4 and having means for withdrawing the switches which actuate the separate drive from the path of the slats after the switches have been actuated by a slat.
6. A machine for cutting Venetian blind slats to length and for punching holes therein for lift cords comprising a die for cutting the slats, a die for punching one hole in the slats, said two dies being fixed in position relative to the machine and to each other so that a slat passes first through the punch die, an additional die for punching a hole in the slats, said third die being movable on the machine to vary the distance between it and the fixed dies, an operating drive for the two fixed dies, a separate drive for the third die, a switch positioned in the path of travel of the slats on the exit side of the cutting die, the distance between the switch and the die being adjustable

in accordance with the length of slat desired, said switch controlling both drives for the dies and being actuated by the end of a slat after it has passed through the die.

7. A machine as described in claim 6 and having a second switch spaced in the path of travel of the slats between the cutting die and the first mentioned switch, said second switch controlling the separate drive for the third die and being actuated by the end of the slat after it has passed through the dies, and means for moving said second switch from the path of the slat after it has been 10 actuated.

8. A machine as described in claim 7 in which the means for moving said second switch from the path of the slat is actuated by the drive for the movable die.

9. In a machine for assembling slats, tapes and lifting cords of a Venetian blind, said machine having dies for cutting and punching the slats and threading heads for assembling the slats, tapes and lifting cords, means for adjusting the position of some of the dies and some of the heads to assemble slats of different lengths comprising, 15 bars operatively connected to each of the movable dies and heads, said bars having rack teeth cut along a face thereof, a shaft, pinions of different diameters on the shaft, one pinion being connected to each of the bars, the diameters of the pinions being proportional to the distance which each die or head is moved to assemble a blind of a particular length, all of said pinions being rotated by their common shaft, and means for turning the shaft.

10. A machine for assembling the slats and a ladder tape of a Venetian blind comprising, means to guide the ladder tape to a point of assembly, means to guide the slats between the cross tapes and side tapes of the ladder tape at said point, and means to lift the slats and the tapes prior to actuation of said slat guiding means to said succeeding slats to said point of assembly, means for supporting the tapes and slats after assembly in a closely stacked arrangement and in a position removed from the place of assembly.

11. A machine as described in claim 10 and having a gate adjacent the point of assembly, said gate extending across the path of the cross tapes of the ladder tape as they are brought to said point, said gate being operable to permit only one cross tape at a time to reach the point of assembly.

12. A machine as described in claim 10 and having a switch which controls the feeding of slats through the machine, said switch having operating means which are movable in and out of the path of travel of the slats, said switch being actuated by the end of a slat when it is in the path of travel of the slats, and means for moving the switch operating means out of said path.

13. A machine as described in claim 10 and having means for detachably carrying a bracket on said support for assembled slats and tapes, said bracket being adapted to support a switch for controlling the operation of the machine, the switch being positioned in the path of travel of the slats through the machine and being actuated by a slat as it passes through the machine.

14. A machine as described in claim 10 and having a vertically fixed and horizontally movable support for a Venetian blind head rail adjacent said point of assembly.

15. A machine as described in claim 10 and having a vertically fixed and horizontally movable support for a Venetian blind head rail adjacent said point of assembly and a stop against which one end of the head rail may abut when the machine is in position in accordance with the width of the blind being assembled, and means for moving the machine.

16. A machine for assembling the slats, a ladder tape and lifting cords of Venetian blinds comprising, a guide for a tape, guides for passing slats through the side and cross tapes of the ladder tape, a needle adapted to be inserted in a lifting cord hole in the slats, said needle having at one end a clamp for securing a lifting cord

to the needle, means for raising the slats after they have passed into the tapes and the needle has been inserted in a lifting cord hole, the raising of the slats also raising the tapes, and means for lifting the needle at timed intervals to permit slats to pass through the tapes.

17. A machine as described in claim 10 in which the guide for the ladder tape comprises, a block having a vertical passageway through which the cross tapes of the ladder tape may pass, said passageway having two sides which slope towards each other in the direction in which the tapes pass through the block.

18. A machine as described in claim 10 and having means for retaining the slats and tape after they have been assembled, said means comprising arms extending vertically above the point of assembly and on each side of the slats, each arm having a spring latch extending towards the other arm, each latch being opened by a slat as it is lifted between the arms and closing beneath the slat after it has passed the latch.

19. A machine as described in claim 10 and having means to spread the cross tapes and side tapes of the ladder tape to facilitate passing slats therethrough, said means comprising levers pivoted at one end and rotatable about their pivots to swing their free ends against the side tapes adjacent the cross tapes and means to rotate the levers.

20. A machine as described in claim 10 in which the guide means for the slats comprises tubular members U-shaped in section and means for tilting said members to release the slats after they are in the ladder tape.

21. A machine as described in claim 16 and having means to retain the needle in position in a lift cord hole in a slat, said means comprising a socket beneath the slat into which one end of the needle may be inserted, and means on the needle and in the socket for detachably securing the needle in the socket.

22. A machine as described in claim 16 and having means to retain the needle in position in a lift cord hole in a slat, said means comprising a socket beneath the slat into which one end of the needle may be inserted, two legs forming the end of the needle which is inserted in the socket, openings in each leg, and laterally extending projections in the socket adapted to fit into said apertures when the needle is inserted in the socket.

23. A machine as described in claim 16 in which the guide for the ladder tape comprises, a member having a vertical passageway extending at right angles to the path of the slats and through which all of the cross tapes pass, said member also having two sockets, one on each side of the tape guide into which said needle may be inserted after it has passed through a lifting cord hole in a slat, and means to reciprocate said member in a path parallel to the path of the slats whereby the needle may be inserted into the sockets alternately and thereby 55 place the cross tapes on alternate sides of the needle.

24. A machine as described in claim 10 in which the guide for the ladder tapes comprises, a block having a vertical passageway through which the cross tapes of the ladder tape may pass, and a gate extending across the passage and operable to permit only one cross tape at a time to pass out of said passageway.

25. In a machine for assembling the slats, ladder tapes and lifting cords of Venetian blinds, means for threading lifting cords through holes therefor in the slats comprising, an elongated member, a clamp at one end of the member for engaging a lifting cord, means at the other end to engage and disengage supports therefor on the machine and thereby hold said member in different positions in the machine and means for actuating said engaging and disengaging means.

26. In a machine for assembling the slats, ladder tapes and lifting cords of Venetian blinds, a needle for threading lifting cords through holes therefor in the slats, said needle having at one end a clamp for engaging a lifting cord, and two legs extending generally parallel to each

other and forming the other end of said needle, said legs being adapted to engage another part of the machine and retain the needle in position in the machine.

27. In a machine for assembling the slats, ladder tapes and lifting cords of Venetian blinds, a needle for threading lifting cords through holes therefor in the slats, said needle having at one end a clamp for engaging a lifting cord, two legs extending generally parallel to each other and forming the other end of the needle, and apertures in the legs adjacent said end and adapted to engage matching projections in another portion of the machine and thereby retain the needle in position in the machine.

28. A machine for assembling slats, ladder tapes and lifting cords of Venetian blinds comprising dies for cutting slats from long lengths of slat material and dies mounted at a predetermined location for punching holes therein for lifting cords at locations in the slat material at a predetermined distance from the ends of the slats, means for creating a releasable feed of slat material for feeding it longitudinally through the dies and to positions for assembly in the tapes, slat supporting means at said assembly positions in line with the path of slat material through the dies, and removed from the dies in the direction of travel of the slat material through the dies, lifting cord feed means mounted at spaced locations relative to each other and at the same spaced distance that the holes are spaced from each other in the slat, switch means in line with the advancing slat material and at a distance from said lifting cord feed means to stop the slat with the holes therein located in position for actuation of said lifting cord feed means, said switch means being operable by the slat material as it passes from the dies through the assembly positions for actuating the cutting and punching dies to cut and punch the slat material and momentarily stop the movement of the slat material through said assembly positions so that holes for lifting cords punched in the slat material are at said assembly positions, a tape guide adjacent each assembly position for guiding a ladder tape to each of said assembly positions, means actuated by said switch means for activating said lifting cord feed means, a support positioned vertically above the assembly positions for holding the tapes and slats after assembly in a closely stacked arrangement, slat lifter means controlled by said switch means for actuating said slat lifters for lifting the slats from said assembly positions to said stacked position, said switch means being so constructed and arranged that the aforesaid cycle of operation is repeated after a slat is lifted from said switch means.

29. A machine for assembling slats, ladder tapes and lifting cords of Venetian blinds comprising a die in fixed position for cutting the ends of slats, a second die for punching a hole for a lifting cord in said slat, said second die being spaced a fixed distance from the first die, a third die for cutting additional lift cord holes in said slat, said third die being movable in relation to the first

two dies, threading heads for guiding ladder tapes to points of assembly of the tapes with slats which have been cut and punched, the threading head nearest the dies being fixed in position, the other heads being movable towards and away from the fixed head, means for feeding slats in long lengths through the dies and the side and cross tapes of the ladder tapes in the threading heads, and means for adjusting the position of the movable dies and threading heads relative to the fixed dies and fixed threading head in accordance with the length of the blind being assembled, said adjusting means comprising a toothed rack operatively connected to each movable die and movable threading head, pinions of different diameters mounted on the same shaft and each operatively connected to one of said racks whereby rotation of the shaft will move the die and the threading heads a distance proportional to the diameter of the pinion to which it is operatively connected.

30. A machine as described in claim 29 and having in addition a stop carried by the movable threading head farthest from the cutting die whereby a head rail for the blind being assembled can be placed between the cutting die and the stop and said common pinion shaft rotated until the die and the stop abut opposite ends of the head rail thereby determining the setting for the movable die and the movable threading heads in accordance with the width of the blind to be assembled.

31. A machine for cutting Venetian blind slats to length and for punching holes therein for lift cords comprising a die for cutting the slats, a die for punching one hole in the slats, said two dies being fixed in position relative to the machine and to each other, an additional die for punching a hole in the slats, said third die being movable on the machine to vary the distance between it and the fixed dies, an operating drive for the two fixed dies, a separate drive for the third die, means whereby the two drives can be connected together whereby the drive for the fixed dies also drives the movable die, the separate drive being disconnected, and means for operating said drives to produce slats of varying length and varying number of holes.
